US00D833891S

(12) **United States Design Patent** (10) Patent No.: **US D833,891 S**
(45) Date of Patent: **** Nov. 20, 2018**

(54) **WATCH**

(71) Applicant: **SALVATORE FERRAGAMO S.P.A.**,
Florence (IT)

(72) Inventor: **Roberto Russo**, Milan (IT)

(73) Assignee: **SALVATORE FERRAGAMO S.P.A.**,
Florence (IT)

(**) Term: **15 Years**

(21) Appl. No.: **35/503,568**

(22) Filed: **Feb. 20, 2017**

(80) **Hague Agreement Data**

Int. Filing Date: **Feb. 20, 2017**

Int. Reg. No.: **DM/094993**

Int. Reg. Date: **Feb. 20, 2017**

Int. Reg. Pub. Date: **Aug. 25, 2017**

(51) **LOC (11) Cl.** **10-02**

(52) **U.S. Cl.**

USPC **D10/32**

(58) **Field of Classification Search**

USPC D10/30-32, 38-39

CPC G04B 37/0008

See application file for complete search history.
